Samuel W. Gibbs, of Albany, N.Y.

Assignor to

J. H. Ransom, of same place.

Letters Patent No. 1211, dated Mar. 20, 1860.

The schedule referred to in these Letters Patent and making part of the same.

250

Des. 1211

Full where it may seem.

Be it known that I, Samuel H. Gibbs, of the City of Albany in the County of Albany and in the State of New York, have invented or produced a new and original design for the Tops and Bases of Sheet Iron Stoves, and I do hereby declare, that the following is a full and exact description of the same, reference being had to the accompanying drawings and to the letters of reference marked theron.

A. represents the Base of said Stove with ornaments occurring around it and forming when placed in their position and proper intervals, an ornamental base, or bottom plate of an Oval sheet iron Stove.

B. represents the top of said Stove with ornaments placed at proper intervals and forming in combination an ornamental top of the said Stove.

C. represents the cover for the top of the said Stove carved and ornamented, which in combination form the ornamental top cover for the said Stove.

D. represents the purn usually placed on the cover of said Stove to give an ornamental finish, carved and ornamented to correspond with the general ornamentation of the said Stove.

E. represents the door of the said Stove, closing against the frame F. and forming in combination the ornamental door and frame of the said Stove.

(What I claim as my invention or production and desire to secure by Letters Patent is the ornamental design and configuration of the top, base, and door and frame of a sheet iron Stove as herein described, and shown in the accompanying perspective drawing.
